UNITED STATES PATENT OFFICE.

GRANT B. SHIPLEY, OF PITTSBURGH, PENNSYLVANIA.

WOOD-TREATING CYLINDER.

1,144,669.

Specification of Letters Patent. Patented June 29, 1915.

Application filed November 22, 1913. Serial No. 302,523.

To all whom it may concern:

Be it known that I, GRANT B. SHIPLEY, resident of Pittsburgh, in the county of Allegheny and State of Pennsylvania, have invented a new and useful Improvement in 5 Wood-Treating Cylinders, of which the following is a specification.

This invention relates to vertical treating cylinders for use in wood preserving installations.

The object of the invention is to provide 10 a vertical treating cylinder in which the operations of charging and discharging the same may be carried on at a level with the top of the cylinder, and one which effects 15 its object by timber supporting means arranged to be lowered gradually in the cylinder during charging and discharging of the same, so that the upper portion of the pile 20 of timbers thereon may be maintained substantially level with the top of the treating cylinder.

A further object of the invention is to 25 provide a vertical treating cylinder possessing the foregoing qualities and which is capable of accommodating timbers of relatively large size, as for instance railway cross ties.

In the accompanying drawings, Figure 1 30 is a vertical sectional view of the treating cylinder; and Fig. 2 is a view showing the vertical treating cylinder in elevation and also illustrating one arrangement of means for use in conjunction with said vertical 35 cylinder for charging or discharging the same.

The treating cylinder 1 is vertically disposed and as shown in Fig. 1 is supported in position by means of shores 2. It may, 40 however, be designed to rest directly on the platform or on the ground, or may, if desired, be sunk in the ground so as to bring its top substantially on a level with the surface. The top 3 of the cylinder is formed 45 to be entirely removable and the opening at the top of the cylinder is of a diameter substantially equal to that of the cylinder in order to permit of the introduction of large timbers for treatment. In the cylinder is a 50 vertically movable platform 4, which as illustrated, is movable vertically by means of the power plunger 5 of a suitable hydraulic or other power cylinder 6. The platform is provided on its under side with 55 guide wheels 7 coöoperating with guide rails 8 in order to relieve the plunger of strains

due to an unbalanced loading of the platform.

The operations of charging and discharging the cylinder take place at its upper extremity, and, as the pile of ties increases upon the platform 4, it may be lowered, so that the work is always carried on at a level with the top of the treating cylinder until said cylinder is completely charged with timber. The top is then placed in position and a preserving fluid introduced by any suitable means and the charge of timber treated for any necessary length of time, after which the top is removed and the ties 60 are discharged from the cylinder, the level of the top of the pile of ties or timbers in this operation, as in the operation of charging, being at all times even with the level of the top of the cylinder. Any suitable arrangement of mechanism may be used for raising and lowering platform 4, the power plunger illustrated being merely the preferred form of actuating means. The platform 4 may be raised and lowered by means 65 of cables secured to the platform and passing over the guide sheaves at the top of the cylinder and over a suitably actuated winding drum, by which means an effect similar to that produced by the power plunger is 70 obtained.

When the cylinder is erected in a position elevated above the surface of the ground, as is preferred, means for raising timbers to the top of the cylinder and lowering them 75 therefrom must necessarily be provided. In Fig. 2 one form of means adapted for performing this work is shown diagrammatically in conjunction with the treating cylinder. This charging and discharging means 80 is shown as a piling machine or elevator 9, running upon a track 10 adjacent to the cylinder, and an endless chain conveyer 11 adapted to convey timbers from any suitable source of supply to a point adjacent the 85 treating cylinder.

The piling machine 9, as illustrated, comprises an endless chain 12 running over a guide sheave 13 at the upper extremity of the frame of the machine, over take-up 90 sheaves 14, and around the guide sheave 15 mounted at the outer end of a pivoted arm or boom 16. The piling machine illustrated is thus adapted to remove ties or timbers from storage piles to conveniently 95 place them in suitable means, as for instance the conveyer 11, for transportation to the

treating cylinder, and to elevate them therefrom to the top of a cylinder.

The treating cylinder described has the great advantage that it reduces the labor necessary in placing timber to be treated in the cylinder and removing it therefrom. When a piling machine of the general nature of the one described is used, it is merely necessary in charging or discharging the cylinder that one man may be stationed at the top of the treating cylinder and another at the foot of the piling machine to handle the timbers during the operation of either charging or discharging the cylinder. The vertical cylinder described reduces materially the cost of the labor employed in the process of wood treating over that incurred with the horizontal type of cylinder in general use, since with the latter type it is necessary to load and secure the timber to be treated upon some type of creosoting car arranged to be run into the cylinder, or to introduce the timber into the cylinder by means involving even more labor. It is obvious that the cylinder described is adapted for use with a great variety of means for charging and discharging the same, the means actually shown being merely illustrative of the general mode of operation in treating wood by means of this cylinder.

What I claim is:—

1. A vertical wood treating cylinder having in its top a receiving and discharge opening, a platform in said cylinder upon which the charge is supported, and means for raising and lowering said platform so arranged that throughout the operations of loading and unloading the top of the charge upon said platform may be maintained sub-

stantially level with the top of the treating cylinder.

2. A vertical wood treating cylinder having in its top a receiving and discharge opening of a diameter substantially equal to the diameter of the cylinder chamber, a platform in said cylinder upon which the charge is supported, and means for raising and lowering said platform so arranged that throughout the operations of loading and unloading the top of the charge upon said platform may be maintained substantially level with the top of the treating cylinder.

3. A vertical wood treating cylinder having in its top a receiving and discharge opening, a vertically movable charge supporting platform in said cylinder, and a power plunger for raising and lowering said platform so arranged that throughout the operations of loading and unloading the top of the charge upon said platform may be maintained substantially level with the top of the treating cylinder.

4. A vertical wood treating cylinder having in its top a receiving and discharge opening, a vertically movable charge supporting platform in said cylinder, and mechanism arranged to be operated to lower said platform in said cylinder gradually during the operation of placing the charge thereon and similarly raise the same as the charge is removed therefrom.

In testimony whereof, I have hereunto set my hand.

GRANT B. SHIPLEY.
